Primary Examiner — Susan Bennett Hattan*Assistant Examiner* — Vy Koenig(74) *Attorney, Agent, or Firm* — William F. Bahret(57) **CLAIM**

The ornamental design for a stool seat, as shown and described.

DESCRIPTION

FIG. 1 is a perspective view of a stool seat showing our new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines in FIG. 1 show environment for illustrative purposes only and form no part of the claimed design.
